Primary Examiner—Holly H Baynham*Assistant Examiner*—Cynthia M Chin(74) *Attorney, Agent, or Firm*—Amster, Rothstein & Ebenstein LLP(57) **CLAIM**

The ornamental design for a squirting toy, as shown and described.

DESCRIPTION

FIG. 1 is a perspective view of a squirting toy showing my new design;

FIG. 2 is a front side view thereof;

FIG. 3 is a back side view thereof;

FIG. 4 is a right side view thereof; and,

FIG. 5 is a bottom plan view thereof.

The broken lines represent portions of the design that form no part of the claim.
